UNIVERSAL FILTER BODY HEAD

Walter J. Kudlaty, Elmhurst, Ill., assignor to Marvel Engineering Company, Chicago, Ill., a corporation of Illinois

Filed Feb. 13, 1964, Ser. No. 78,629

Term of patent 14 years

(Cl. D46—1)

I claim:

The ornamental design for a universal filter body head, as shown and described.
